CLAIM

The ornamental design for an electronic device, as shown and described.

DESCRIPTION

FIG. 1 is a top, front perspective view of an electronic device showing our new design;

FIG. 2 is a bottom, front perspective view thereof;

FIG. 3 is a bottom, rear perspective view thereof;

FIG. 4 is a rear, top perspective view thereof;

FIG. 5 is a top view thereof;

FIG. 6 is a right side view thereof;

FIG. 7 is a bottom view thereof;

FIG. 8 is a left side view thereof;

FIG. 9 is a front view thereof; and,

FIG. 10 is a rear view thereof.

The broken lines illustrate structure or features which form no part of the claimed design.

The drawings include surface shading which illustrates contour, not surface ornamentation. The oblique shading illustrates a transparent surface.
